VACUUM-CLEANER BAG

Ragnar K. Österdahl, Essingen, Sweden

Application March 11, 1938, Serial No. 195,370
In Sweden March 19, 1937

11 Claims. (Cl. 183—51)

This invention relates to vacuum cleaners and more particularly to bags adapted to be attached to the same to receive more or less coarse sweepings and, preferably, also the dust collected by the cleaner, and it is an object of my invention to provide a replaceable and destructible bag for such purpose, which may be made very cheaply, supplied to the consumer at a very low price and can be shipped and stored in a completely flattened shape, even though it has in use an outwardly extending annular flange for its safe fastening to the cleaner.

Another object of my invention is to provide a vacuum-cleaner bag that can be secured to the vacuum cleaner by means of an outwardly extending flange which can easily be collapsed, so as to avoid the escape of dust and dirt from the bag, when the latter is removed from the container.

Other objects and advantages of my invention will appear from the following detailed description in connection with the accompanying drawings, in which:

Fig. 1 is a longitudinal view, partly in section, of the main parts of a vacuum cleaner illustrating the improved bag in place.

Fig. 2 is a side view of the flat bag.

Fig. 3 is an end view of the opened bag ready for insertion into the cleaner.

Figs. 4—7 illustrate some steps of manufacturing the bag.

Fig. 8 illustrates a part of the bag.

Fig. 9 illustrates, partly in section, a modified embodiment of the improved flat bag.

Fig. 10 illustrates a modified part of the bag shown in Fig. 9.

Fig. 11 illustrates another modified part of the bag shown in Fig. 9.

Fig. 12 is a sectional view showing a modified embodiment of the mouth of the bag shown in Fig. 9.

Referring in detail to the drawings, Fig. 1 shows the air-pervious bag 1 in place within the casing 2 of the vacuum cleaner which encloses the motor driven fan 45. The inserted bag has an annular, radially extending flange 3 which is clamped between a ring 40 and a cover 4. The bag 1 is placed within a bag 42 of cotton which has a metal flange 41 that is clamped between the ring 40 and an annular flange 5 of the casing 2. The opening 6 in the cover 4 is connected with the suction nozzle (not shown) of the cleaner, and the opening 7 of the casing is the outlet for air passing through the fan 45.

As shown in Fig. 2, the bag is composed of a

mouth portion 8 and a perforated body portion 9 which has flaps 10 cut out in its wall. In the manufacture of the bag a band 16 of paper or another suitable sheet material is provided with transverse creases 11 and 12, a longitudinal crease 13 and creases 14 extending diagonally between the creases 11 and 12, as shown in Fig. 4. These creases have the effect of pleating the mouth portion of the bag. Thereafter, the band 16 is folded transversely along the creases 11 and 12, as shown in Figs. 5 and 6, whereafter a strip 15 is glued to the folded band immediately below the crease 13 to retain the lower part of the folds 17 of the band 16. Thereafter, an edge 19 of the band 16 is doubled, as shown in Fig. 7. Then the band 16 is glued to an edge of a web 18 of perforated paper or another suitable perforated sheet material, so that the lower parts of the folds 17 are collapsed between the band 16 and the sheet 18. The perforations of the sheet 18 are formed by the cut out flaps 10 the ends of which have suitably narrow and fragile connections 21 with the sheet 18. Thereafter, bag blanks are cut out, and said blanks are folded along definite folding creases to form a collapsed bag that has a sealed satchel bottom 22, as shown in Fig. 2. All parts of the bag consist preferably of paper or another suitable combustible material. The bag thus manufactured is very cheap as it can be manufactured completely automatically in a slightly modified machine for making commercial paper bags. One or a plurality of the vacuum-cleaner bags can be enclosed in their flattened state in a flat envelope, since the portion of the bag that is adapted to form an annular attaching flange forms a direct extension of the bag when the latter is collapsed. Thus they can easily be packed, stored, shipped and distributed and even though, when in use, they are intended to form a substantially cylindrical collector having an outwardly extending annular flange for a particularly safe attachment. For the purpose of inserting the bag into the cleaner casing 2 the folded mouth 8 is bent outwards to form a substantially annular flange 3 (Fig. 3) which obtains a regular polygonal shape as the creases 14 facilitate a regular unfolding of the folds 17. When the mouth 8 is bent outwards its doubled portion 19 is unfolded. The forming of the flange 3 is effected very easily and exactly along the upper edge of the retaining strip 15 and the crease 13 can assist thereby. Therefore, there is no danger that the bag will be inserted into the cleaner in an incorrect position which might cause rupture of the bag when in use subjected

to air pressure and the load of collected dirt and dust. Furthermore, no uncontrolled deformation of the bag will occur when subjected to air pressure.

It is provided by way of example that the bag now described is intended itself merely to trap relatively coarse particles, such as fibrous matter, and to let through air and fine dust through the flaps 10 the connections 21 of which are ruptured when the bag is subjected to suction. Thus this bag has substantially for its object to collect fibrous matter, so that the cleaner can be in use for a very long time before it will be necessary to release and clean the ordinary fabric bag. I have experienced that the disagreeable task of cleaning the outer fabric bag 42 will not be necessary until after a very long time of use, since the felted fibrous matter trapped by the perforated paper bag will form an air-pervious layer that allows air to pass but traps all dust. After the perforated bag has been filled sufficiently, the cover 4 is removed and the bag 1 is drawn out of the casing 2 after the levers 20 have been released. The folded mouth of the bag can easily be collapsed by hand to close the bag to avoid the escape of dirt and dust therefrom. Then the bag with its contents is discarded or burned. Also the bottom of the bag may be perforated.

The bag illustrated in Fig. 9 has an elastic porous filler 23 consisting of fibrous lignocellulose enclosed within the wall 9 and an inner open-work wall or lining 24 which affords large openings 25. I have found by experience that a filler of fibrous lignocellulose is particularly well adapted for the purpose as it will not be unduly felted when the bag is in use or stored. In the manufacture of the bag illustrated in Fig. 9, the filler 23 is first glued to a web of open-work lining leaving margins 26 and 27 extending beyond the filler. Thereafter, a web of paper having cut out flaps 10 covering its perforations is glued at some points to the filler. The folded band 8 is made substantially in the manner heretofore described but it is provided by way of example that a flat band 28 is doubled on and glued to both sides of a margin of the folded band 8. Thereafter, the band 28 is glued to the margin 26 and to the adjacent edge of the wall 9, so that an air tight joint is obtained. The margin 27 of the lining 24 is tightly attached to the wall 9 by means of a strip 29 which is glued to the inner side of the wall 9 and to the margin 27. The blank thus formed with the mouth portion is cut, folded and sealed in the same manner as mentioned above to constitute substantially a satchel bag of paper or similar suitable combustible material. The manufacture of the bag can be carried out completely automatically on forming a continuous band composed of the outer wall, a filler, a lining and a folded band which is fed through the machine. Possibly, a corrugated, air-pervious filler 31, as shown in Fig. 10, may be substituted for the fibrous filler 23. As shown in Fig. 11, the filler might be covered with a fibrous coating 46 of lignocellulose or another suitable material. Said coating serves to trap coarser impurities whilst the filler 9 serves to trap dust or the like. In the embodiment shown in Fig. 12 the band 8 is glued to the inner side of the wall 9. A strip 44 of paper or another suitable sheet material is glued to the margin 26 of the lining as well as to the band 8, so that an air tight joint is obtained. Such an attachment might be arranged also in the embodiment shown in Figs. 2 and 3. The filler may be saturated

with one or more suitable matters adapted to adhere dust, absorb moisture of the air as well as a disinfecting matter or an odorous matter to refresh the air passing through the cleaner.

5 As the bag with its mouth portion can be flattened completely it can be enclosed hermetically within an envelope, the additional matters will not evaporate or be destroyed when the bags are stored. The bag inserted into the vacuum cleaner assumes when in use a substantially cylindrical shape conforming to the annular shape of its mouth, but it is likely to resume its original flat shape when the suction effect is changed. Thus the porous or fibrous filler or coating has a self-cleaning tendency due to pulsatory movements of the bag walls.

When using the bag now described, having an air straining filler or coating, no separate dust collector is needed. I have experienced that the bag having substantially the shape of an ordinary commercial paper bag is sufficiently resistant to withstand, without additional supporting means, the internal air pressure to which it is subjected when in use. For the purpose of clearness the thickness of the fillers is shown exaggeratedly in Figs. 9 to 12.

Where in the accompanying claims I have defined the direction of extent of the annular flange portion of the bag mouth when applied in operating position in a vacuum cleaner as extending radially, it is to be construed as meaning that the flange need not be exactly radial, but that as long as it has an extent in the radial direction with respect to the bag axis, the purpose will be accomplished and the terms of the definition satisfied.

I claim:

1. A vacuum-cleaner bag, having a collapsible mouth portion formed with pleats extending longitudinally of the bag and being adapted to be bent outwards to form a radially extending substantially annular supporting flange for attachment to the vacuum cleaner, the upper edge portion of said pleated collapsible mouth portion being doubled to hold said pleats in their collapsed condition, said pleats being permanently secured against unfolding at a distance from the end of said mouth portion corresponding to the desired width of said flange, said upper edge portion being free to be unfolded by bending the mouth portion to form said flange.

2. A vacuum-cleaner bag, having a collapsible body portion and a collapsible mouth portion having substantially the same width as said body portion and forming a longitudinal extension thereof, said collapsible mouth portion consisting of a strip attached at one edge to said body portion and having collapsible pleats extending in the longitudinal direction of said body portion, said pleats being stuck together at said edge, said mouth portion being adapted to be bent outwards on unfolding said pleats to form a radially extending substantially annular flange extending laterally beyond said body portion for attachment to the vacuum cleaner.

3. A vacuum-cleaner bag, having a collapsible body portion, a collapsible mouth portion of substantially the same width as said body portion and forming a longitudinal extension thereof, said mouth portion consisting of a strip attached at one edge to said body portion and having collapsible folds forming pleats extending in the longitudinal direction of said body portion, and another strip adhesively applied to said edge of said pleated strip transversely to

said body portion to retain said pleats in flatly folded condition at a distance from the upper edge of said mouth portion, said mouth portion being adapted to be bent outwards on unfolding the upper part of said collapsible pleats to form a radially extending substantially annular flange extending laterally beyond said body portion for attachment to said vacuum cleaner.

4. A vacuum-cleaner bag, having a collapsible body portion and a collapsible mouth portion of substantially the same width as said body portion, said collapsible mouth portion forming a longitudinal extension of said body portion and having folds forming pleats extending in the longitudinal direction of said body portion, said mouth portion being adapted to be bent outwards on unfolding said pleats to form a radially extending substantially annular flange extending laterally beyond said body portion for attachment to the vacuum cleaner, said pleats being formed to impart to said flange a polygonal periphery.

5. A vacuum-cleaner bag, having a collapsible body portion and a collapsible mouth portion of substantially the same width as said body portion, said mouth portion forming a longitudinal extension of said body portion and having collapsible folds forming pleats extending in the longitudinal direction of said body portion, said mouth portion being adapted to be bent outwards on unfolding said pleats to form a radially extending substantially annular flange extending laterally beyond said body portion for attachment to the vacuum cleaner, said pleats having creases extending diagonally between their longitudinal edges.

6. A vacuum-cleaner bag, having a collapsible body portion, a collapsible mouth portion of substantially the same width as said body portion, and a bottom which is foldable in flat relationship to said body portion and said mouth portion, said collapsible mouth portion forming a longitudinal extension of said body portion and having collapsible folds forming pleats extending in the longitudinal direction of said body portion, said mouth portion being adapted to be bent outwards on unfolding said pleats to form a radially extending substantially annular flange extending laterally beyond said body portion for attachment to the vacuum cleaner.

7. A vacuum-cleaner bag, having a collapsible mouth portion comprising collapsible pleats extending longitudinally of the bag and being adapted to be bent outwards to form a substantially annular radially extending supporting flange for attachment to the vacuum cleaner, said pleats being secured against unfolding at a distance from the end of said mouth portion defining the width of said flange, the difference between the circumferential length of the material forming said mouth portion and the circumferential length of said mouth portion when collapsed being not less than 2π times said distance.

8. A vacuum-cleaner bag, having a collapsible body portion and a collapsible mouth portion of substantially the same width as said body por-

tion, said collapsible mouth portion forming a longitudinal extension of said body portion and having collapsible folds forming pleats extending in the longitudinal direction of said body portion, said mouth portion being adapted to be bent outwards on unfolding said pleats to form a radially extending substantially annular flange extending laterally beyond said body portion for attachment to the vacuum cleaner.

9. A vacuum-cleaner bag, having a collapsible body portion composed of an outer wall and a lining of fibrous air-straining material, and a collapsible mouth portion of substantially the same width as said body portion, said mouth portion forming a longitudinal extension of said body portion beyond said lining and having collapsible folds forming pleats extending in the longitudinal direction of said body portion, said mouth portion being adapted to be bent outwards on unfolding said pleats to form a radially extending substantially annular flange extending laterally beyond said body portion for attachment to the vacuum cleaner, said body portion and said mouth portion being collapsible to form a flat and smooth lining and envelope completely covering said lining.

10. A vacuum-cleaner bag having a collapsible body portion composed of an outer wall and a corrugated lining of air-straining material, and a collapsible mouth portion of substantially the same width as said body portion, said mouth portion forming a longitudinal extension of said body portion beyond said lining and having collapsible folds forming pleats extending in the longitudinal direction of said body portion, said mouth portion being adapted to be bent outwards on unfolding pleats to form a radially extending substantially annular flange extending laterally beyond said body portion for attachment to the vacuum cleaner, said body portion and said mouth portion being collapsible to form a flat and smooth lining and envelope completely covering said lining.

11. A vacuum-cleaner bag, having a collapsible body portion composed of an outer perforated wall and a lining of fibrous air straining material, a collapsible mouth portion having substantially the same width as said body portion and forming a longitudinal extension of said body portion beyond said lining and having collapsible folds forming pleats extending in the longitudinal direction of said body portion, said mouth portion being adapted to be bent outwards on unfolding said pleated folds to form a substantially annular flange extending laterally beyond said body portion for attachment to the vacuum cleaner, and a sealing strip for connecting said lining to said outer wall, said mouth portion being attached to the inside of the upper edge of said outer wall and said strip extending transversely of said body portion and being attached at its upper edge to the inside of said mouth portion to prevent the upper filter edge from getting loose from said outer wall when said mouth portion is folded outwardly.
